UNITED STATES PATENT OFFICE.

CHARLES F. BURGESS, OF MADISON, WISCONSIN.

METHOD OF MAKING REFRACORY ARTICLES.

No. 884,463.

Specification of Letters Patent. Patented April 14, 1908.

Application filed May 31, 1906. Serial No. 319,598.

To all whom it may concern:

Be it known that I, CHARLES F. BURGESS, a citizen of the United States, residing at Madison, in the county of Dane and State of 5 Wisconsin, have invented certain new and useful Improvements in Methods of Making Refractory Articles, of which the following is a specification.

This invention is a method of producing 10 articles of refractory material and more particularly such articles as require for their effective treatment the use of an electric furnace.

The method consists in forming the article 15 with or without a bonding material, and heating the same to such temperature as may be required, usually to a temperature sufficient to frit or fuse together the constituent particles. During the heating the surface 20 of the article is preferably defined by means of a layer of material which differs in character from the article to be produced and which, after the heating, permits the clean separation of the article by preventing the 25 adherence of adjacent articles or of portions of the adjacent charge.

The method will be described as applied to articles of magnesia in the form of crucibles, tubes or bricks, but it is not restricted 30 to this material or to any particular form or article.

For a full understanding of the invention reference is made to the accompanying drawings, wherein—

35 Figure 1 is a central vertical section showing an arrangement of apparatus suitable for the production of crucibles or similar forms; Fig. 2 is a plan view of the apparatus shown in Fig. 1; Fig. 3 is a vertical longitudinal section illustrating the method as applied to the manufacture of tubes; and Fig. 4 is a transverse vertical section of an electric furnace illustrating the application of the method to the production of bricks and other forms.

40 Figs. 1 and 2 illustrate an arrangement of apparatus suited for the production of crucibles or other vessels of magnesia or other refractory material. In said figures 1, 1 represent vessels of refractory material such as 45 carbon containing a charge 2 of the material to be treated, consisting in the present instance of magnesia in a state of substantial purity. Centrally disposed in said charge is a conductor 3 of carbon or graphite of size 50 and shape conforming to the interior of the vessel to be produced and so constructed as

to serve as a resister for applying heat to the charge. As shown, the resister 3 comprises a carbon or graphite cylinder or rod, subdivided for a portion of its length as indicated at 4, the sections being separated at the top by mica or other insulation 5. The resister, or the several resistors where a number of articles are produced simultaneously as shown, are then inserted between fixed 60 graphite blocks or conductors 6, 6, in such manner as to make effective electrical contact therewith. The current, applied through the terminal conductors 6, traverses the several resistors, as will be readily understood.

In the production of articles in the apparatus as above described, the surfaces adjacent to the source of heat are sufficiently smooth and regular, but the surfaces remote 75 from the resister are usually quite irregular in contour, owing either to differences in the heat development in different portions of the resister or to differences in the heat conductivity of the charge. I have found that this 80 objection can be overcome by defining the surface of the article to be produced by means of a layer of material indicated at 7, said material differing in character from the charge. If heat be applied to the charge to 85 fuse or frit the constituent particles of the same, such fusion or fritting being carried to or beyond the boundaries defined by the layer 7, it will be found that the portions of material outside of the surface marked or defined by the layer 7 are readily separable at such surface, the result being that the contour of the article conforms to the original 90 position of the layer 7.

I do not limit myself to any particular material for the layer 7, though I prefer to use paper or other combustible or carbonizable material, and I find that by the use of such material a formed article having smooth and regular surfaces may be readily prepared.

95 Fig. 3 illustrates the application of the method to the preparation of tubes of magnesia or other refractory material. 1 represents furnace walls inclosing a chamber which is traversed by a carbon or graphite 100 resister 3 corresponding in diameter to the bore of the tube to be produced. The charge 2, which may consist of magnesia, is packed around the resister, the portion of the charge which is to constitute the finished 105 tube being enveloped by the layer 7, preferably of paper as above described. Heat is

applied to fuse or frit the magnesia within the limits defined by the layer 7 and usually to some distance beyond the same, the heating being such as to insure the effective treatment of all material within these limits; the tube may thereafter be removed and any adherent loose or fused or fritted material separated as above described.

Fig. 4 illustrates the method as applied to the manufacture of refractory articles such as bricks or blocks. These are first molded or otherwise formed of the dimensions required, any of the usual bonding materials being used if desired, and are then stacked in an electric furnace adjacent to resistors 3, the articles being separated by layers 7 of paper or wrapped therein as indicated in the figure. The articles may be surrounded and covered by a loose body of the same material as indicated at 8. The layer 7 serves as before to permit a clean and free separation of the articles, and to prevent welding thereto of adjacent articles or of adjacent portions of the walls or loose charge.

It will be understood that the method as illustrated by Fig. 3 is applicable to articles of any contour, such articles being preferably bedded in a body of loose refractory material. In case the articles are first molded or shaped into the form required the layer 7 may obviously be applied in the form of a coating of paint, differing in character from the body of the article, and serving to define the surface of the article and capable of preventing the adherence or welding thereto of adjacent materials.

I claim:—

1. The method of producing articles of re-

fractory material, which consists in defining a surface of the article in a body of material of like character by means of a layer of material differing therefrom in character, and applying heat to produce the article, substantially as described. 40

2. The method of producing articles of refractory material, which consists in defining a surface of the article in a body of material of like character by means of a layer of carbonizable material, and applying heat to produce the article, substantially as described. 45 50

3. The method of producing articles of refractory material, which consists in defining a surface of the article in a body of material of like character by means of a layer of paper, and applying heat to produce the article, substantially as described. 55

4. The method of producing articles of magnesia, which consists in first molding or otherwise forming the article and then applying sufficient heat to frit or fuse together 60 the constituent particles, substantially as described.

5. The method of forming articles of refractory material, which consists in first molding or otherwise forming the article, applying a layer of material differing therefrom in character to a surface thereof, and applying sufficient heat to frit or fuse together the constituent particles, substantially as described. 65 70

In testimony whereof, I affix my signature in presence of two witnesses.

CHARLES F. BURGESS.
